UNITED STATES PATENT OFFICE.

HARRY C. TURNER, OF LOS ANGELES, CALIFORNIA.

SHOCK-ABSORBER.

1,009,454.

Specification of Letters Patent. Patented Nov. 21, 1911.

Application filed August 21, 1907. Serial No. 389,440.

To all whom it may concern:

Be it known that I, HARRY C. TURNER, a citizen of the United States, residing in the city of Los Angeles, county of Los Angeles, 5 State of California, have invented new and useful Improvements in Shock-Absorbers, of which the following is a specification.

This invention relates to improvements on my invention for which Letters Patent 10 No. 819,386, dated May 1st, 1906, were granted me and also on my invention shown and described in my application for Letters Patent bearing S. N. 297,457, filed January 28, 1906, and allowed August 2, 1907; and 15 the object thereof is to provide a novel arrangement of parts which enables the use of an annular spring in place of a coiled spring and which also enables the casing in which the parts are placed to be rendered 20 liquid tight so that the wearing parts may be completely surrounded by a lubricant which enhances their wearing qualities and renders their action uniform.

I accomplish this object by means of the 25 device described herein and illustrated in the accompanying drawings in which:—

Figure 1,—is a side elevation of my improved shock absorber showing its application to a vehicle. Fig. 2,—is a vertical section of the absorber, the section through the 30 ratchet being taken on line 2—2 of Fig. 3. Fig. 3,—is a section taken on line 3—3 of Fig. 2. Fig. 4,—is a section taken on line 4—4 of Fig. 2. Fig. 5,—is a section taken 35 on line 5—5 of Fig. 2. Fig. 6,—is an enlarged detail of the means for preventing the case from unscrewing due to the jarring action of the vehicle.

Referring to the drawings 10 designates 40 a portion of a vehicle frame and 11 a portion of the frame supporting springs. Upon the passage of the vehicle over an obstruction or uneven surface, spring 11 at first is forced upwardly and subsequently 45 frame 10 carrying the body tends to rise by the action of the compressed spring. It is the object of my absorber to allow a free and unimpeded upward movement of the spring with the full spring resiliency but 50 to so restrict the upward movement of the frame that the frame and body will not be thrown violently upward with attendant discomfiture of passengers and possible breakage of the spring by being carried 55 above its normal position. To this end casting 11 of the absorber is secured by bolts 12

to frame 10 and connecting bar 13 is connected to a pivot 14 on spring clip 15 being adapted to oscillate lever 16 to which it is pivotally secured at 17. Lever 16 is formed 60 integrally with plug 18 as shown in Fig. 2, which projects into sleeve 19, being rotatively secured thereto by means of key 20 forming an integral part of plug 18. Sleeve 19 extends beyond the end of plug 18 and 65 encompasses a boss 21 on rear member 22 of case 11. A bolt 23 passes longitudinally through plug 18 and screws into boss 21 to the bottom of the bore therein as shown in Fig. 2 and holds plug 18 from slipping out 70 of sleeve 19, at the same time forming a bearing for the plug so that when lever 16 is moved the plug will not move out of alignment and bind the different working parts. Cap 24 is internally threaded and adapted 75 to screw onto rear member 22 as shown in Fig. 2, a spring clip 25 mounted on the rear member being adapted to enter notches 26 in the rear edge of the cap and prevent the same from unscrewing. Cap 24 is provided 80 with a central bearing 27 which surrounds sleeve 19 at its outer end and is provided with a stuffing box 28 adapted to render liquid tight the joint between sleeve 19 and bearing 27. From the above description it 85 is manifest that sleeve 19 will be rotated when lever 16 is oscillated by any relative movement of the vehicle body and springs.

The mechanism about to be described is designed to permit the rotation of sleeve 19 90 in one direction without any appreciable retardation but to present an adjustable resistance to the rotation of the sleeve in the opposite direction, which is the direction in which sleeve 19 moves when the vehicle 95 body moves away from the spring.

Mounted on sleeve 19 and rotatively secured thereto by means of four projecting keys 30 is a sleeve 31 which is provided on its periphery with a series of ratchet teeth 32. Rotatively mounted on ratchet sleeve 31 are two plates 33 and 34 which carry between them spring pressed dogs 35 adapted to engage ratchet teeth 32 upon the upward movement of frame 10. Dogs 35 are 100 five in number and ratchet teeth 32 are sixteen in number and thus only one dog is in engagement with the ratchet teeth at one time and it will be observed that upon the rotation of sleeve 31 through the distance 110 corresponding to the length of one tooth there will be five engagements of the teeth.

by the dogs. Thus the lost motion of the ratchet teeth is reduced to a minimum while the action of the dogs on the same is positive.

5 On the rear side of plate 33 and between that plate and rear member 22 of case 11 is a friction plate 40 whose configuration is shown in Fig. 4, the plate shown being the other friction plate of the device which is 10 constructed similarly to plate 40. Both of these plates are provided with inserted friction plugs 41 of fiber or cork adapted to furnish the requisite amount of friction between the plates on either side of the friction plate. A second friction plate 42, similar to friction plate 40, is loosely mounted 15 on sleeve 31 adjacent plate 34 between plate 34 and a stationary plate 43 held from rotation by means of lugs 44 on its periphery engaging key ways 45 in rear member 22. An annular spring 46 in the shape of a frustum of a cone is interposed 20 between stationary plate 43 and cap 24, being adapted to press stationary plate 43 against friction plate 42 and hold the same in engagement with rotating plate 34 and at the same time press rotating plate 33 against friction plate 40. Cap 24 is 25 screwed down upon member 22 to provide the necessary compressive pressure in annular spring 46 and the necessary friction between rotating plates 33 and 34 and friction plates 40 and 42. The friction plates are free to rotate and the movement may 30 take place between the friction plates and the stationary plates as well as between the friction plates and the revolving plates.

From the foregoing description it will be observed that no appreciable resistance will 40 be offered to the movement of my shock absorber in one direction while any desired amount of resistance may be offered to the movement in the opposite direction. As the friction plates wear down, the wear being 45 followed up by the actions of the annular spring, the cap may be screwed down upon the base member to afford the necessary compression for the efficient working of the device. The entire case is filled with a lubricant, preferably of semi-liquid consistency 50 and is prevented from running out of the case by packing box 28 provided especially for that purpose. The immersion of the friction plates in a lubricant renders the life 55 of the plates longer than is possible with any other arrangement, renders the action of the friction plates uniform until they are completely worn out, completely lubricates all bearings not intended to produce 60 friction, and renders the action of the dogs noiseless.

Having described my invention what I claim as new and desire to secure by Letters Patent is:—

65 1. In a shock absorber a stationary case, a

revoluble sleeve mounted in said case, a screw cap adapted to close said case and through which said sleeve projects, means mounted on the outer end of said sleeve to rotate the same, a revoluble member in said case connected to said sleeve by ratchet means, friction plates mounted on each side of said revoluble member, one of said friction plates bearing against the stationary case, a stationary plate bearing against the outer face of the other of said friction plates, said stationary plate having a transverse movement to and from said friction plate but being prevented from rotation, and an annular spring between said stationary plate and said cap adapted to be pressed by said cap against said stationary plate and hold said friction plates and said revoluble member in engagement with each other. 70

2. In a shock absorber a stationary case, a screw cap for said case, a sleeve revolvably mounted in said case and projecting outwardly through said cap, an oscillating lever mounted on the end of said sleeve, said lever adapted to be operated by the relative movements of a vehicle frame and springs, a ratchet member keyed to said sleeve within said case, a revoluble member loosely mounted on said ratchet member, said revoluble member being provided with a plurality of spring pressed dogs adapted to engage said ratchet member and adapted to rotate said revoluble member together with said ratchet member in one direction and allow said ratchet member to rotate in the opposite direction without rotating said revoluble member, friction plates on each side of said revoluble member, one of said friction plates bearing against said stationary case, a stationary plate adapted to bear against the outer face of the other of said friction plates, said stationary plate being prevented from rotary movement but having a transverse movement to and from said plate, and an annular spring between said stationary plate and said cap adapted to press said stationary plate against said friction plate. 95

3. In a shock absorber a stationary case, a screw cap for said case, a sleeve revolvably mounted in said case and projecting outwardly through said cap, said cap being provided with a packing gland around said sleeve, an oscillating lever mounted on the end of said sleeve, said lever adapted to be operated by the relative movements of a vehicle frame and springs, a ratchet member keyed to said sleeve within said case, a revoluble member loosely mounted on said ratchet member, said revoluble member being provided with a plurality of spring pressed dogs adapted to engage said ratchet member and adapted to rotate said revoluble member together with said ratchet member in one direction and allow said ratchet mem- 100 110 115 120 125 130

ber to rotate in the opposite direction without rotating said revoluble member, friction plates on each side of said revoluble member, one of said friction plates bearing 15 against said stationary case, a stationary plate adapted to bear against the outer face of the other of said friction plates, said stationary plate being prevented from rotary movement but having a transverse movement to and from said plate, and an annular spring between said stationary plate and said cap adapted to press said stationary plate against said friction plate.

4. In a shock absorber a case, a revoluble

shaft mounted within said case and projecting outwardly therefrom, a packing gland mounted on said case around said shaft, a disk mounted on said shaft, loose friction plates on each side of said disk, a screw cap for said case, and an annular spring between 20 said cap and one of said friction plates.

In witness that I claim the foregoing I have hereunto subscribed my name this 13th day of August, 1907.

HARRY C. TURNER.
